CLAIM

The ornamental design for a carbonating machine, as shown and described.

DESCRIPTION

FIG. 1 is a perspective view of a carbonating machine showing our new design in accordance with the invention; FIG. 2 is a right side elevation view thereof;

FIG. 3 is a left side elevation view thereof;

FIG. 4 is a front view thereof;

FIG. 5 is a rear view thereof; and,

FIG. 6 is a bottom view thereof.

The broken lines in the drawings depict portions of the carbonating machine that form no part of the claimed design.
